CARBURETOR

Hugh S. Brown, Wauwatosa, and Werner E. Armstrong and Joseph V. Reichenbach, Milwaukee, Wis., assignors to Briggs & Stratton Corporation, Milwaukee, Wis., a corporation of Delaware

Application September 10, 1949, Serial No. 114,982

4 Claims. (Cl. 123—119)

1

This invention relates to carburetors and refers particularly to carburetors especially adapted for use on single cylinder internal combustion engines.

One of the chief objects of this invention is to simplify and reduce the cost of such carburetors without sacrificing full economy, good performance and adequate engine power.

With a view toward satisfying this objective, it is another object of this invention to provide a carburetor in which the customary float feed is supplanted by a simple suction tube through which fuel is lifted directly from the tank to the jet in response to engine suction manifested at the jet.

In this connection it is another object of this invention to provide a carburetor wherein the body not only provides a fuel mixture passage but also constitutes a load carrying member in that it has the fuel tank suspended from the underside thereof.

Again with a view toward simplicity and low cost it is a further object of this invention to form the body of the carburetor as a die casting so designed and shaped as to provide an open topped cylindrical well to receive a barrel-like throttle valve which is held in place by interengaging abutments so placed on the die cast body and the valve that disengagement thereof requires rotation of the valve to a position beyond one of its normal limits of rotation.

Another object of this invention is to provide a simple choke for the carburetor which lends itself well to assembly with the die cast body.

Another object of this invention is to provide a carburetor of the character described having governor actuated means for controlling the position of the throttle valve and hence the speed of the engine and a novel manner of adjusting the spring against which the governor acts with a view toward facilitating access and manipulation of the screw by which this adjustment is effected.

In this connection it is another object of this invention to so dispose the adjusting screw for the tension spring that access thereto may be had from the same side of the carburetor body at which the needle valve screw is adjusted, and with both adjustment screws positioned in the space directly above the fuel tank to be protected from underneath by the tank.

Another object of this invention is to provide for remote control of the throttle while at the same time retaining governor control therefor.

With the above and other objects in view which

2

will appear as the description proceeds, this invention resides in the novel construction, combination and arrangement of parts substantially as hereinafter described, and more particularly defined by the appended claims, it being understood that such changes in the precise embodiment of the hereindisclosed invention may be made as come within the scope of the claims.

The accompanying drawings illustrate one complete example of the physical embodiment of the invention constructed in accordance with the best mode so far devised for the practical application of the principles thereof, and in which:

Figure 1 is a perspective view showing a portion of a one cylinder internal combustion engine with the carburetor of this invention applied thereto, the air cleaner being omitted in this view;

Figure 2 is a top plan view of the carburetor, again with the air cleaner removed, and with a part of the flange upon which the air cleaner sets broken away to better illustrate the choke valve;

Figure 3 is a side view of the carburetor with parts broken away and in section;

Figure 4 is a cross sectional view taken through Figure 3 on the plane of the line 4—4;

Figure 5 is a horizontal sectional view taken through Figure 3 on the plane of the line 5—5;

Figure 6 is a side view similar to Figure 3 but illustrating the manner in which remote control is provided for the throttle;

Figure 7 is a fragmentary side view showing a slightly modified form of remote control; and

Figure 8 is a detail sectional view through Figure 7 on the plane of the line 8—8.

Referring now particularly to the accompanying drawings in which like numerals indicate like parts throughout the several views, the numeral 5 indicates generally the carburetor of this invention. The body 6 of the carburetor is an elongated hollow die casting having a longitudinally extending bore 7 opening to one end of the body, and an attaching flange 8 at said end. The attaching flange provides means by which the body is securable to the cylinder 9 of an engine.

The engine, of course, may be of any desired construction with its cylinder either vertical as shown or horizontal. In any event when the carburetor is secured in place on the cylinder the mouth of its bore 7 which provides a mixture or induction passage opens to the intake port 10 of the engine and the body 6 projects horizontally outwardly from the cylinder as a rigid load carrying member.

At its outer end portion the body has a down-

wardly projecting bracket 11 having a flat bottom wall 12. This bracket serves to strengthen the body and its flat bottom wall provides a gasket flange to which a fuel tank 13 is secured with a gasket H interposed therebetween. The top and bottom walls of the tank are substantially flat and parallel, and the top wall thereof is reinforced by a plate 15 into which the mounting screws are threaded.

The extreme outer end portion of the tubular body has an upstanding hollow boss 16 formed thereon, the hollow interior of which defines a well communicating with the bore 7 through an air inlet opening 16' in the bottom thereof. A flange 17 at the top of this boss provides a base upon which a conventional air cleaner 18 is seated, the air cleaner being held in place in the customary manner by a tension screw 19 extending downwardly through the center thereof and anchored as at 20. Thus with the carburetor mounted on the engine cylinder in the manner described engine suction draws air into the outer end of the mixture passage provided by the bore 7. Engine suction also draws fuel from the tank into the mixture passage through a jet indicated generally by the numeral 21.

The jet 21 is located in a socket 22 extending axially into a boss 23 formed on the side of the body. A plurality of orifices 24 provide restricted communication between the jet socket and the mixture passage, and a needle valve seat 25 threaded into the socket coacts with a needle valve 26 to meter the flow of fuel into the mixture passage. Engine suction manifested at the jet draws fuel into the socket 22 outwardly of the needle valve through a suction pipe 27 which extends down through the bottom of the bracket and the top wall of the tank to have its lower open end terminate slightly above the bottom wall of the tank. A screen 28 is preferably secured over the open lower end of the suction pipe to preclude the admission of foreign matter into the pipe, but otherwise the suction pipe is open, no check valve being needed due to the direct lift suction action.

The manner in which the suction pipe is held in place is another example of the simplicity and low cost which characterizes this invention. As shown in Figure 4, the bottom wall 12 of the bracket from which the suction pipe depends is formed with an annular V-shaped groove 29 surrounding the hole into which the suction pipe fits and the adjacent portion of the pipe is slightly reduced in diameter before being assembled with the body. After the pipe is inserted into the body the inner peripheral edge of the groove 29 is pressed inwardly, thus locking the suction pipe in place.

Attention is also directed to the fact that the head 30 of the needle valve adjusting screw is accessible at the side of the body above the fuel tank and that the axis of the screw lies in a plane parallel with the top wall of the tank and substantially perpendicular to the axis of the mixture passage 7. The advantage of this location of the needle valve adjusting screw will be apparent hereinafter.

Adjacent to the point at which the fuel jet opens into the mixture passage the body 6 has an upright cylindrical valve socket or well 31 intersecting its bore 7. The bottom of this socket or well is closed but the top is open. Seated in the socket is a barrel-like throttle valve 32. This valve, like the body 6, is made as a die casting and has upper and lower cylindrical end portions

33 and 34 respectively connected by a flattened middle portion or vane 35. The bottom of the socket is below the bore 7 and its top opens through the top of a boss 36 the upper portion of which forms a circular neck surrounding the mouth of the socket. The cylindrical end portions of the valve are thus journaled in the socket above and below the bore 7 while the flat middle portion 35 extends directly across the bore to control flow therethrough. Since the valve turns on a vertical axis there is little chance of its binding in the socket, and to further reduce the likelihood of binding, its area of contact with the bottom of the socket upon which it rests is reduced to a minimum through the provision of a small central foot or pad 34' projecting down from the bottom of the valve. It is to be noted that the axis about which the throttle valve turns lies in a vertical plane which is normal to the axis of the induction passage and intersects the wall thereof at a point closely adjacent to the orifices 24. Hence one edge of the vane 35, which constitutes the throttle valve proper and functions in the manner of a butterfly valve, swings to and from a position directly adjacent to the mouths of the orifices 24. This positional relationship, which is best shown in Figure 5, provides a simple manner of securing the desired balance for the carburetor since by slightly shifting the location of the orifices 24 lengthwise of the induction passage and hence with respect to the orbit of the throttle valve, the relative effect of engine suction upon air and fuel injection may be varied.

35 It will also be seen that since the socket 22 lies to one side of the induction passage and is at substantially the same elevation above the top of the fuel tank as the induction passage, the height to which the fuel must be lifted is held to a minimum.

36 The upper cylindrical end 33 of the valve has a head 37 formed integrally therewith, the underside of which has an annular groove 38 to receive the neck provided by the upper portion of the boss 36. This interengagement between the neck surrounding the mouth of the valve socket and the head 37 of the valve provides a free running seal between the valve and the mouth of the socket.

50 Since the body 6 constitutes a load carrying member it is desirable to provide as much reinforcement therefor as possible. To this end side ribs 39, a top rib 40 and a bottom rib 41 are formed along the length of the body to merge with the attaching flange 8. The top rib 40 is interrupted by the boss 36 which defines the top of the valve socket, and at one side of this boss the rib 40 is enlarged to provide a stop 42 and at the other side thereof the rib 40 is undercut to provide an overhanging ledge 43. This ledge 43 coacts with a segment-like flange 44 integral with the head 37 of the valve to hold the valve in the socket except when the valve is turned beyond one of its normal limits 60 of rotation.

65 One of these limits of rotation is defined by the engagement of a radial arm 45 projecting from the head of the valve with one side of the stop 42. The position thus defined is the full open position of the valve. The other or idling position is defined by the engagement of a screw 46 with the stop 42, the screw 46 being adjustably threaded in another arm 47 extending radially from the head of the valve. A spring 66 70 encircling the screw 46 bears against the under-

side of its head and thus frictionally holds the screw in adjusted position.

As will be readily apparent the adjustability of the screw 46 enables the valve to be turned far enough in a counterclockwise direction (as viewed in Figure 2) to bring the segment-like flange 44 clear of the overhanging ledge 43. This manner of securing the valve in position is particularly advantageous in assembly since it merely requires dropping the valve into its socket and threading the screw 46 into proper position.

Another expedient designed to facilitate assembly and thus reduce the cost of the carburetor is the manner in which the choke valve indicated generally by the numeral 48 is designed. The function of the choke valve is, of course, to regulate the amount of air admitted into the carburetor mixture chamber. Hence, it is mounted directly adjacent to the air inlet and consists merely of a slide valve 49 longitudinally slidabie in a guideway 50 formed in the top face of a bracket 51 extending outwardly from the closed outer end of the body which is slotted as at 52 to accommodate the inner end of the slide valve. The slide valve 49 is thus movable across the air inlet opening 16' in the bottom of the hollow boss 16 to regulate the passage of air through the opening into the mixture passage 7 provided by the hollow interior of the body.

The valve 49 is held in place by a friction plate 53 overlying the top of the valve and which in turn is drawn downwardly and secured against displacement by a spring 54 coiled about the lower end of a rivet 55, the rivet extending down through the friction plate 53, an elongated slot in the valve and the bracket 51, and the spring 54 being confined between the lower head of the rivet and the bottom of the bracket. Any suitable means, not shown, may be provided for sliding the valve 49 back and forth to control the amount of air entering the mixture passage.

Inasmuch as the carburetor of this invention is designed especially for use in small portable single cylinder engines which often are called upon to operate entirely unattended, it is desirable to provide an automatic control for the throttle valve to thereby coordinate the speed of the engine with the load imposed thereon. Such controls, of course, are not new in themselves, Patent No. 1,660,079 issued to Perry E. Mack, being an example thereof.

As in the aforesaid patent the control here employed also utilizes a vane 56 mounted to be influenced by air pressure emanating from the ventilating fan blades 57 on the fly wheel 58 of the engine, this air blast being directed and guided by a shroud 59. The blade 56 which is secured to a hinged actuator arm 60 is adapted to be moved toward the right in Figure 1 by the air blast. Such movement of the blade and arm 60 is imparted to the throttle valve through a wire link 61 to rotate the valve toward its idling position and thus slow up the engine whenever the engine speeds up due to a diminishing load.

Though, as will be readily appreciated, the end of the wire 61 could be hooked directly to some part of the throttle valve, to simplify the die casting thereof a stamped sheet metal attaching clip 62 is provided for this purpose. This clip is conveniently held in place by the idle adjusting screw 46. To this end the clip has a part 64 which overlies and embraces the arm

47 on the valve where it is held by the screw 46 and its holding spring 63.

The response of the governor vane 58 to air pressure is opposed by a spring 65, the tension of which determines the speed at which the engine will run. The manner in which this spring is adjusted is another feature designed with a view toward achieving utmost simplicity and convenience. One end of the spring is hooked into a loop 66 formed in the wire link 61. Its other end is hooked onto a lever 67 pivoted to swing about a horizontal axis toward and from the spring 65. A screw 70 provides the pivot for the lever 67 and also clamps a stamping 68 to the side of a boss 69 which forms part of the body bracket 11. This detail is shown in Figure 5.

The stamping 68 has an arcuate part 71 bent back to form an inclined cam surface across which the free end of the lever 67 swings so that a screw 72 threaded into the lever and bearing against the inclined cam 71 increases the tension on the spring 65 as the screw 72 is threaded farther into the lever 67. The screw 72 thus constitutes the speed adjusting screw, and to hold the same against accidental displacement from adjustment a compression spring is interposed between its head and the outer face of the lever 67.

Since the head of the screw 72 faces in the same direction as the head 30 of the needle valve screw and since these screws are parallel and relatively closely adjacent to each other, adjustment of the needle valve and the tension of the spring 65 to determine the speed at which the engine will run may be simply and conveniently accomplished.

It is to be noted that whereas the throttle valve is moved in one direction by the governor mechanism and in the other direction by the spring 65, there are no forces acting upon the valve in a way which could cause it to bind in its socket. The spring is tensioned directly between the governor arm 60 and the adjustable lever 67, and motion of the governor arm 60 produced either by the spring or the air blast is translated into rotation of the throttle valve through the link 61. The spring force is thus not carried through the throttle valve to the governor.

If the pull of the spring in anywise imposes a side thrust upon the valve, as is common in carburetor controls of the past, the resulting tendency to tilt the valve in its socket causes it to stick or bind and thereby render the automatic control of the engine unreliable.

This particular manner of adjustably anchoring the spring 65 also lends itself well to remote control of the spring tension and consequently the governor maintained engine speed. Thus as shown in Figure 6, by removal of the screw 72 and connection of a remote control wire 74 to the lever 67 it is possible to quickly and easily adjust the lever and consequently the tension of the spring. The wire 74 slides in a flexible sheath 75 which is anchored in a boss 76 forming part of the bracket 11.

The arrangement shown in Figure 6 provides no means for retaining the lever 67 in adjusted position and depends upon whatever means are employed for actuating the wire 74 to perform this function; whereas the arrangement shown in Figures 7 and 8 does provide means for frictionally holding the parts in adjusted position. As here shown the lever 67 is replaced by a longer lever 77 and the arcuate part 71' of the stamping

68' instead of being bent down to form a cam is left flat to have the lever 77 slide thereacross as it swings about its pivot.

A spring tensioned friction clamp 78 carried by the lever 77 engages the other side of the arcuate arm 71' as shown in Figure 8 to frictionally hold the lever in any adjusted position. The lever 77 is, of course, movable back and forth in any suitable manner either directly or by means of a remote control wire (not shown).

Attention is directed to the fact that the attaching flange 8 of the carburetor body has four bolt holes and that the cylinder has only two tapped holes for the reception of the cap screws 79 by which the flange 8 is bolted to the cylinder. Also the bolt holes of the flange 8 are equispaced so that either set of its diametrically opposite holes may be aligned with the tapped holes in the engine cylinder. Thus the carburetor body may be secured to the engine cylinder in either of two positions ninety degrees apart. This enables the carburetor to be upright whether its cylinder is vertical or horizontal, so that in either position the bottom 12 of the bracket and consequently the fuel tank 13 is horizontal.

As shown the fuel tank is relatively shallow. This minimizes the height the fuel has to be lifted. It is, of course, desirable to hold this height to a minimum but in actual practice it has been found that as long as the fuel does not have to be lifted much more than two inches the slight change in mixture resulting from the increased lift is not at all serious.

From the foregoing description taken in connection with the accompanying drawings it will be readily apparent to those skilled in the art that the carburetor of this invention is far simpler and less expensive to produce than carburetors heretofore used on small portable single cylinder engines. It will also be clear that one of its chief advantages lies in the fact that it obviates the need for a float bowl and float. This advantage, of course, results from the suspension of the fuel tank directly beneath the fuel jet so that the fuel may be drawn by suction directly up to the jet in such quantity as determined by the setting of the needle valve. Another advantage of this arrangement is that the suction tube or pipe requires no check valve at the foot.

Other advantages of the instant construction, which will no doubt be clear from the foregoing description, are the simplicity with which the speed adjustment is effected, the simplicity of the choke valve and of the throttle valve mounting and the convenience of the way in which remote control may be applied.

What we claim as our invention is:

1. In a carburetor for internal combustion engines: a hollow elongated body providing a mixture passage opening to one end of the body, and an attaching flange on said end of the body having two sets of diametrically opposite bolt holes disposed at ninety degrees to each other and through either of which screws may be passed for securing the arm to an engine cylinder over the mouth of its intake port, one set of holes being used for vertical engines and the other for horizontal engines, in either case the body being in the same position of rotation about its longitudinal axis.

2. As an article of manufacture an elongated tubular body for a carburetor, adapted when in use, to occupy a horizontal position, said body comprising: a casting having a bore providing a mixture

passage, the axis of the bore being straight; an upstanding hollow boss at one end of the body providing an air inlet and an upwardly facing horizontal seat for an air cleaner; another boss extending upwardly from the body medially of the ends of the bore and having a cylindrical bore extending axially down into it with its axis intersecting that of the longitudinal bore of the body to rotatably mount a throttle valve; a flange at the bottom of the body and against which the top of a fuel tank may be secured; a boss formed on the side of the body above said flange, said last named boss having a socket therein communicating with the longitudinal bore through a restricted orifice, said socket being adapted to receive a needle valve, there being a bore extending down from the socket and communicating the socket interior with the exterior of the casting through the bottom thereof to receive a suction pipe; and an attaching flange on the body at the end of its bore opposite the air inlet.

3. As an article of manufacture, a body for a carburetor, comprising: a casting having a horizontal longitudinally extending mixture passage; an upstanding boss at one end of the body having an upwardly opening well therein providing an air inlet to the mixture passage and having an upwardly facing seat for an air cleaner surrounding the mouth of the well; another boss extending upwardly from the body intermediate the ends thereof and having a substantially vertically disposed bore therein communicating with the mixture passage and open at its top so that a throttle valve operating in the mixture passage may have a part thereof project through the bore to be accessible for the adjustment of the throttle valve from above the body; a flange at the bottom of the body and against which the top of a fuel tank may be secured; the body having a socket therein above said flange and communicated with the mixture passage at one side thereof, said socket being adapted to receive a fuel jet; the body having a bore extending down from the socket and through the bottom of said flange to receive a suction pipe; and an attaching flange on the body at the end thereof opposite the air inlet.

4. An engine carburetor, comprising: a body having a bore providing an induction passage open at one end and having an air inlet into the induction passage remote from its open end; means on the body for mounting the same upon an engine cylinder with the open end of the induction passage discharging into the intake port of the cylinder and with the axis of the induction passage horizontal; a shallow fuel tank; a flange on the bottom of the body with its underside at an elevation close to the bottom of the induction passage; means securing the top of the fuel tank to the underside of the flange with the induction passage axially parallel with the normal level of fuel in the tank; the body having a substantially cylindrical fuel jet socket therein extending laterally from one side of the induction passage and at substantially the same elevation above the top of the tank as the induction passage and with its axis substantially horizontal, said socket having restricted communication at its inner end with the induction passage through an orifice opening to the induction passage at a point between the air inlet and its open end; a suction pipe extending down from said socket through the flange and into the fuel tank with its lower end near the bottom of the tank; a needle valve in said socket between its connection with the suction pipe and the orifice to control the flow

of fuel into the induction passage; the suction pipe and jet socket providing for fuel admission to the orifice and hence the induction passage for the idling as well as the running condition of the engine so that the needle valve controls the flow in each instance; and a butterfly type throttle valve mounted in the induction passage for swinging motion about an axis normal to the axis of the induction passage and in a vertical plane which intersects the wall of the passage directly adjacent to the point at which said orifice opens to the induction passage.
